(57) **CLAIM**

The ornamental design for a hair straightening iron with brush, as shown and described.

DESCRIPTION

1.1 is a top-front-left perspective view of a hair straightening iron with brush showing my new design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

In the drawings, the broken lines illustrate portions of the article which form no part of the claimed design.
